UNITED STATES PATENT OFFICE.

HARRY L. FILLIUS, OF WASHINGTON, DISTRICT OF COLUMBIA.

FOLDING STRETCHER.

1,151,932.

Specification of Letters Patent. Patented Aug. 31, 1915.

Application filed November 13, 1912. Serial No. 731,200.

To all whom it may concern:

Be it known that I, HARRY L. FILLIUS, a citizen of the United States, residing at Washington, District of Columbia, have invented certain new and useful Improvements in Folding Stretchers, of which the following is a specification, reference being had therein to the accompanying drawing.

The aim of my invention has been the production of a stretcher which may be folded and unfolded with the least number of operations, and without difficulty or delay even by the most unexperienced. And I have so far succeeded that the stretcher of my invention may be unfolded and in turn folded by two operations only, the one the simple and obvious unfolding longitudinally of the side poles, and the other the simple moving of the extended side poles apart from each other to stretch the canvas covering, or bringing them together to collapse the same.

The stretcher of my invention is complete in every detail, simply and strongly built, is mechanically most efficient in operation and durable, and at the same time of simple, straight, attractive lines and of the light construction adapting it for ready transportation—yet the two simple operations only are required for each of its unfolding and folding movements, the unfolding and folding movements and the locking of all parts being controlled through the simple manipulation of the side poles as specified. The side poles may be most conveniently manipulated in all cases by direct grasp of the grips on their ends, which fact insures the preservation of order in the handling of the stretcher, prevents mishandling, and reduces to a minimum the time required. There is no chance of jockeying about for holds in the unfolding, or the feverish pulling and pushing of miscellaneous strapping, locking and bracing devices.

The details of my invention are shown in the accompanying drawings and will be described with reference thereto.

Of the drawings—Figure 1 is a perspective view showing the stretcher of my invention with the canvas covering removed for the purpose of clarity. Fig. 2 shows one part of one of the side poles and a connected

leg in extended position. Fig. 3 shows one of the side poles with its connected legs in folded position. Fig. 4 is a plan view of the hinge joint of the side poles in extended position. Fig. 5 is a side elevation of the same. Figs. 6 and 7 are transverse sections on lines 6—6 and 7—7 respectively of Fig. 5.

The side poles are designated generally 10—10. They are each made in two halves *a*—*b* connected together by the downwardly opening hinges 11—11.

The side poles are spaced apart by folding spacing rods 12 pivotally connected at their opposite ends with the side rods 10 and folding inwardly at the middle as shown in dotted lines in Fig. 1. To each end of each side pole is pivotally connected a leg adapted to be moved about its pivot into and out of position alongside of the side pole to which it is attached.

The canvas covering (not shown) is stretched over the top of the side poles, and is secured either to the outsides of the poles 75 or to their under sides as may be preferred.

Within the body of the part *a* on each side pole (or within the body of the part *b* if preferred), are located close to the hinge pin 13, but on the opposite or under side of 80 the pole, two oppositely moving transversely arranged locking bolts 14, sliding in socket 15 which is extended through the adjacent side plates 16 of the hinge connected with member *a*. The side plates 17 of the hinge 85 connected with the member *b* are extended to form projections or hinge ears 18, which when the side poles are extended as shown in Figs. 4 and 5, overlap the side plates 16 connected with the member *a* of the pole. 90 In these overlapping portions are formed sockets 19 adapted to register with the socket 15 in the plates 16 connected with the member *a* when the pole is extended as shown, whereby the two transversely arranged sliding locking bolts 14 may be moved in opposite directions into the registering sockets 15—19, to lock the hinged joint open and the side rod in extended position. Thus the side rod cannot collapse 100 when the load strain comes upon it. By suitably proportioning the size of the hinge plates and the size of the locking bolts 14 and hinge pins 13, I have succeeded in mak-

ing the strength of this joint as great as is needed for any service. The locking bolts 14 and the registering sockets 15 and 19 are made circular and accurately fitting, where-
5 by the joint is rigid when locked in extended position. Moreover there is no wear at the joint and it retains its rigidity substantially throughout the life of the stretcher.

The locking bolts 14 as aforesaid are
10 locked on the interior of the part *a* of the pole, the view shown in Fig. 5 being taken with the covering plate 20 (see Figs. 6 and 7) removed. Through a transverse lever 21 pivoted at 22 to the part *a* and connected
15 by pins 23 to the scissors levers 24, which in turn are connected with the locking bolts 14 through slots 25 in which their ends bear, the locking bolts 14 may be operated from the exterior of the part *a*, by simply moving
20 the operating lever 21 back and forth. The end of the operating lever 21 projects through a slot 26 in the hinge plates and the entire locking device is inclosed, rendering the structure of the hinge joint es-
25 sentially simple and straight-lined, free of exterior parts which may catch and bind on the canvas covering and give trouble during the folding. The location of the lock within the body permits folding of the side
30 poles in the smallest compass which their substantially uniform cross section will permit.

The operating lever 21 is connected by rod
35 27 extending substantially parallel and on the inside of the side pole (see Fig. 1) to one of the spacing rods 12 on one side of the pivotal connection of the spacing rod to the side pole, whereby, when the side poles have been extended, when they are moved
40 apart, the movement of the spacing rod 12 operates the locking bolts 14 to lock the side poles in extended position.

The legs 121 are connected by rods 28 extending substantially parallel with the
45 side poles, each to the part of the side pole opposite longitudinally to that to which it is attached. This connection 28 is made in each case from a pivotal point 29 above the pivotal connection 30 of the leg with the side pole to the hinge ear 31 or other moving portion on the other end of the pole, whereby when the side poles are folded and ex-
50 tended, the legs 121 have imparted to them movement to and from folded position. One
55 of the connecting rods 28 of each side pole connects to the outside hinge ear of the op-
posite part of the rod (see Figs. 3 and 7), while the other rod 28 of the same side pole connects to the inside hinge ear through
60 an arc-shaped slot 32 in the outside hinge ear. Preferably the pivotal connection to the hinge ear is made by pins 33 fixed on the ends of the rods and held in sockets or pin holes 34 respectively in inner and outer

hinge plates by means of a washer 35 or 65 other means on the transversely extending hinge pin 13. Another construction may be employed if desired but this is simple and easily constructed and assembled.

Pivots connected with each leg 121 is 70 a brace 134 pivotally connected in turn with a small locking lever 35 (see Figs. 1, 2 and 3), in turn pivotally connected at its outer end to the inside of side rod 10. By this outer pivotal connection the movement 75 of the leg 121 into and out of folded position is unobstructed by the brace 134 for the reason that in its movement outwardly (see Fig. 3) the brace 134 carries the locking lever 35 around its pivot to a folded position 80 within the width of the side pole.

The inner end of the locking lever 35 is bent over to coöperate with the locking pro-
jection on the outside of spacing rod 12. The locking projection 35^a on the spacing 85 rod is in extended position shown in Fig. 1, hooks over the end of locking lever 35 and fixes it in position with respect to the side pole 10, whereby the brace 134 is made effec-
tive and the legs are rigidly positioned. 90

The spacing rods 12 are constituted toggles by the formation of their middle joints 36 as locking toggle joints. This is simply done by providing projections 37 and 38 on the hinge which permit the spacing rods to 95 be unfolded to full length from their inner dotted line positions, and then just a little beyond their position of greatest length whereby the stretched canvas maintains the spacing rods in this extended position, their 100 tendency to collapse outwardly being pre-
vented by the abutting projections 37-38. In this position the pivot 36 is without the line of centers between the points of piv-
105 otal connection of the rods 12 to the poles 10. To collapse the rods 12 a slight pres-
sure at the joints 36 only is necessary.

With this understanding of my invention, its manipulation as above described will be most readily perceived. Assuming the 110 stretcher folded, both side rods being folded together as the one side rod is shown in Fig. 3, the hand grips 39 at the ends of the poles are grasped, one pair by each of two persons, and with the side poles still closely 115 side by side, they are unfolded at the hinge joint 11 in a manner similar entirely to the unfolding of the ordinary slide rule. The manipulators are then at opposite ends of the stretcher. By this simple act of unfold-
120 ing, the legs 121 have been moved by the connecting rods 28 to extended position and the legs rest upon the floor or ground as the case may be. It is then necessary only that the side poles be moved apart as shown 125 in dotted lines and as in full lines in Fig. 1, the manipulators simply moving the hand grips 39 apart by spreading their arms

apart. By making these movements suddenly, the rods 12 lock automatically. As a result of this movement, the rod 27 has been moved by the unfolding of spacing rod 12 to throw the locking bolts 14 and render the side poles rigid in extended position. So also the locking levers 35 have been engaged by projection 35^a and the extended legs 121 are rigidly braced in position. The 10 stretcher may be then immediately lifted and carried to a desired point of service, or having been unfolded at the point of service, the burden may be placed upon it and transported to the desired point. It should 15 be noted especially that the two operations just described follow each other consecutively and immediately. If desired a small downward pressure may be put on the grips 39 when the side poles are moved apart, 20 whereby the hinged joints 11 are kept fully open and the operation of the lock is unimpeded. The position of the legs 121 on the other hand may be such as respects the grips and the hinge 11 to require no pressure 25 to be exerted, the weights of the outer ends of the side rods maintaining the hinges in full open position. But the tips of the legs 121 are provided with metal sheaths which move easily over the floor or the ground and 30 no difficulty whatever is experienced in retaining the side poles in extended position until locked.

The operation of folding the stretcher is simply the reverse of that described, the 35 rods 12 being first collapsed and the side poles moved close together, whereupon they may be folded upon each other and together as shown in Fig. 3.

While I have described the best form of 40 my invention now known to me, I wish to have it understood that my invention may be given other forms by those skilled in the art without departing in any wise from the generic spirit of its essential features, and 45 that I desire to cover in the annexed claims all such modifications.

Having thus described my invention, what 50 I claim and desire to secure by Letters Patent is:—

1. A side pole for stretchers made in two 55 portions hinged together and having overlapping hinge plates on each of two opposite sides, said hinge plates being provided with sockets adapted to register when the 60 pole is extended, together with a pair of operatively connected oppositely moving locking bolts mounted transversely of one of said portions and adapted simultaneously to be slid into said sockets when they register to lock the pole in extended position.

2. A side pole for stretchers made in two 65 portions hinged together, together with a locking device located interiorly of one of said portions of the pole, adapted to lock

the hinge joint between said parts in open 65 position, together with means for operating said locking device from the exterior of said pole.

3. A folding stretcher comprising a pair of side poles each made in two parts hinged 70 together, locking devices associated with the hinge joints and adapted to lock the poles in their extended positions, means connecting said side poles and adapted to space the same apart, together with an operating connection between said locking devices and a part of said stretcher with respect to which the poles move when the stretcher is unfolded whereby the locks are automatically operated during the unfolding operation. 75 80

4. A folding stretcher comprising a pair of side poles each made in two parts hinged together, a locking device associated with each hinge joint and adapted to lock the parts of each pole together in extended position, folding spacing rods connecting the two side poles and adapted to space the same apart and a connection between the aforesaid locks and one of the folding spacing rods whereby when the side poles are 90 moved with respect to each other the locks are operated. 85

5. A side pole for a folding stretcher made in two parts hinged together and folding legs fixedly pivoted thereto connected with said side pole one on each side of the hinge joint and operated into and out of folded position through the relative movement of said two parts of the pole, the connection to the legs in each case when 100 the pole is extended paralleling and lying substantially adjacent to the body of the pole. 95

6. A side pole for folding stretchers comprising two parts hinged together and folding legs connected with said pole one on each side of the hinge joint and movable all the way into and out of folded position through connection each with that part of the pole on the opposite side of the hinge 110 joint itself, the said operating connections between the legs and the hinge when the pole is extended lying in substantially the same right line. 105

7. A side pole for stretchers comprising 115 two parts hinged together, the hinge connecting the parts having integrally formed hinge axis ears of considerable radius from the axis of the hinge, folding legs connected therewith and connecting rods between the said legs and the ears of the hinge connecting the parts, said connecting rods being connected to the ears at points removed from the axis of the hinge and the leg on the one part being connected to the hinge ear on the other whereby the legs are folded and unfolded when the pole is folded and unfolded. 120 125

8. A side pole for stretchers comprising two parts hinged together, a folding leg on each part, a connection from the outer hinge ear on the one part to the folded leg on the other, an arc-shaped slot in said outer hinge ear on the one part, and a connection through said arcuate slot from the inner hinge ear on the said other part to the folding leg on the one.
9. A side pole for stretchers comprising two parts hinged together, a folding leg on each part, and connecting rods extending from the said legs to the opposite hinge ears of the said hinge joint between the two parts and said connecting rods being eccentrically connected with said hinge ears whereby relative movement of said two parts of the pole causes the folding and unfolding of the said legs, together with means whereby the hinge pin maintains the two said connecting rods connected with the ears of the hinge.
10. A folding stretcher comprising a pair of side poles, legs on said side poles which are adapted to be moved from folded positions substantially parallel with the rods to extended positions substantially transverse thereof, together with folding transverse spacing rods which when collapsed are free from the legs but which when extended engage and brace the legs in extended position.
11. A folding stretcher comprising a pair of side poles, a pair of folding spacing rods connecting said poles together and adapted to space them apart, and in addition folding legs on one of the aforesaid elements braced in extended position by the other of said elements, said spacing rods having connection with said poles independently of said legs.
12. A folding stretcher comprising a pair of side poles, a pair of folding spacing rods connecting them together adapted to space them apart when extended, and additional independently movable folding legs mounted on one of said elements, and projections from the other group of said elements which engage and brace said legs in extended position.
13. A side pole for stretchers made of two portions hinged together and having in extended position overlapping parts, on opposite sides thereof, a pair of oppositely moving locking bolts mounted transversely of one of said portions and means for simultaneously moving said locking bolts to engage said overlapping parts to lock the pole in extended position on each of its opposite sides.
14. A folding stretcher comprising a pair of side poles made in two parts hinged together, collapsible means connecting the poles together whereby they may be spread and braced apart or collapsed together at will, and locking devices associated with the hinged joints and operated through relative lateral movement of said poles when spread apart to lock the poles in extended positions.
15. A folding stretcher comprising a pair of side poles each made in two parts hinged together, a folding leg connected with each part of each pole and operated into and out of collapsed position through relative movement of the parts of the poles, collapsible means connecting said poles together whereby said poles may be spread and braced apart or collapsed together at will, and abutments for bracing said legs operated into and out of bracing position through the relative movement of said side poles when they are spread apart and collapsed.
16. A folding stretcher comprising a pair of side poles each made in two parts hinged together, a folding leg connected with each part of each pole and operated into and out of collapsed position through relative movement of the parts of the poles, collapsible means connecting said poles together whereby said poles may be spread and braced apart or collapsed together at will, abutments for bracing said legs operated into and out of bracing position through the relative movement of said side poles when they are spread apart and collapsed, together with a lock associated with the hinged joint of each pole and also operated by the relative movement of said poles to lock the poles in extended position.
17. A folding stretcher comprising a pair of side poles each made in two parts hinged together, collapsible means connecting said poles whereby said poles are adapted to be spread and braced apart or collapsed together at will, folding legs connected with said side poles and abutments adapted to brace said legs, moved into and out of bracing position through the relative movements of said side poles with respect to each other.
18. A side pole for stretchers comprising two portions hinged together and a lock adapted to retain said portions in extended positions comprising overlapping parts on each side of the pole, oppositely moving transverse bolts adapted to engage each of the overlapping parts on one side of the pole, and means for simultaneously operating said bolts in opposite directions.
19. A side pole for stretchers comprising two sections hinged together, a leg pivoted to a fixed point on each section and having a rotative movement about said fixed point from an extended position substantially normal to the pole to a folded position substantially parallel thereto, and a connection between each leg and the section of the pole carrying the other leg, said connection being made between points on the leg and section

respectively having equal paths of movement whereby the legs are moved into and out of folded position solely by the relative movement of the sections of the pole.

- 5 20. A folding stretcher comprising a pair of side poles divided intermediate their ends into two section hinged together, a leg on each section moved into and out of folded position by relative movement of the two
10 sections of its pole and independent col-

lapsible connections between the poles having portions which when the connected stretcher is extended, brace the legs in their extended position.

In testimony whereof I affix my signature 15
in presence of two witnesses.
